CLAIM

The ornamental design for a plush toy, as shown and described.

DESCRIPTION

FIG. 1 is a front perspective view of a plush toy showing the new design;

FIG. 2 is a front view thereof;

FIG. 3 is a rear view thereof;

FIG. 4 is side view thereof;

FIG. 5 is a top view thereof; and,

FIG. 6 is a bottom view thereof.

The broken lines shown in the drawings represent portions of the plush toy that form no part of the claimed design.
